CAN OPENER

John R. Sheperak, Detroit, Mich.

Application August 30, 1955, Serial No. 531,331

3 Claims. (Cl. 30—10)

This invention generally relates to a can opener and more specifically provides a punch-type can opener of novel and improved construction wherein the size and position of the aperture formed in the top of a can by the opener may be varied.

An object of the present invention is to provide a demountable wall attached can opener having a pivotal handle thereon integrally formed with a pivotal V-shaped punch for engagement with the tops of tin cans to be opened wherein pivotal movement of the handle will cause penetration of the punch downwardly through the top of the can thereby forming V-shaped apertures therein.

A further important object of the present invention is to provide a can opener in accordance with the preceding object in which pointed members are provided for engaging under the rim of a can for supporting the same and a plurality of such supporting members are provided in spaced relation thereby permitting vertical adjustment of a can in relation to the punch, thereby varying the radial point of contact of the point of the V-shaped punch and varying the size of the opening of the aperture formed thereby.

Other objects of the present invention will reside in its simplicity of construction, ease of attachment, ease of operation, adjusting features, adaptation for its particular purposes and its relatively inexpensive manufacturing cost.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the can opener of the present invention with a can illustrated in dotted line for illustrating the relationship of the elements of the invention;

Figure 2 is a transverse, vertical sectional view taken substantially upon a plane passing along section line 2—2 of Figure 1 illustrating the construction of the two side members and the recess in the bottom of the device for providing access to the cap remover;

Figure 3 is a longitudinal, vertical sectional view taken substantially upon a plane passing along section line 3—3 of Figure 2 illustrating further structural details of the can opener; and

Figure 4 is an exploded group perspective view illustrating the elements of the invention.

Referring now specifically to the drawings, the numeral 10 generally designates the can opener of the present invention including a pair of vertically disposed side plate members 12 and 14 which are rigidly interconnected by bottom portions 16 and 18 wherein one edge of the bottom portions 16 and 18 are interconnected by a bottom ledge or edge 20 formed integrally with the side member 12. The rear terminal vertical edges of the side members 12 and 14 are provided with outwardly extending flanges 22 and 24 which are provided with

2

downwardly converging side edges 26. Attached to and extending between the outer surface of the flanges 22 and 24 is a mounting plate 28 having edges 30 which downwardly converge coextensively with the edges 26 of the flanges 22 and 24. Disposed in a mounting plate 28 between the side members 12 and 14 is a pair of vertically spaced and aligned keyhole slots 32 for engagement with a pair of vertically spaced headed screw fasteners (not shown).

10 For mounting the can opener 10 on a supporting wall surface, a channel shaped mounting bracket generally designated by the numeral 34 is provided, which includes a web portion 36 and outwardly extending legs 38 which terminate in inturned edges 40 thereby forming a channel-shaped guideway wherein the legs 38 are disposed in downwardly converging relation for receiving the converging edges 26 and 30 of the flanges 22 and 24 and the mounting plate 28 for supporting the can opener 10. The web 36 is provided with an offset portion 42 having apertures 44 therein for receiving screw threaded fasteners for the purpose of mounting the bracket 34 on a supporting wall wherein the major portion of the can opener may be removed therefrom thereby forming a portable and readily demountable unit.

25 The upper and outer corners of the side members 12 and 14 are rounded as designated by the numeral 46 and provided with transversely aligned apertures 48 for receiving a pivot bolt 50 extending therethrough for receiving the hinge barrel 52 at one end of an elongated handle 54 which is generally channel shaped at its outer end and provided with a longitudinal rib formed by a longitudinal recess 56. The other end of the hinge barrel 52 is provided integrally with a V-shaped cutter 58 having sharpened edges 60 and a slightly depending pointed free end 62.

30 The free terminal edges of the side members 12 and 16 are provided with inwardly extending notches 64 which define projecting lugs 66 wherein the upper edges of the projecting lugs 66 are provided with downwardly and inwardly inclined edges 68 which intersect with the outer edge of the lugs 66 in an acute angle thereby forming an upwardly extending pointed projection for engagement under the rim 70 of a tin can 72 wherein the top 74 thereof may be penetrated by the punch 58 when the handle 54 is moved downwardly to the position illustrated in dotted line in Figure 1. By positioning the rim 70 of the can 72 in selective notches with selective pointed ends of the lugs 66 engaging under the rim of the can 70, the point of contact between the pointed end 62 of the punch 58 and the top 74 of the can 72 may be varied thereby varying the radial extension of the V-shaped opening in the top 74 and also regulating or varying the size of the opening. It will be understood that the material cut from the top 74 is pushed downwardly alongside the inner surface of the can thereby providing access to the materials therein. The device of the present invention is especially adapted for use with fluid containers and especially those utilized in canning beverages wherein the beverage will be poured from the can for consumption.

35 Also, the side member 14 is provided with an upwardly extending hook shaped recess 76 in the bottom edge thereof between bottom portions 16 and 18 which forms a bottle cap remover.

40 The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A can opener comprising a frame having a pair of spaced parallel side members disposed in vertical relation and terminating in free vertical end edges, a punch pivotally mounted between said side members, an elongated handle extending integrally from said punch for moving the punch, said free end edges of said side members having vertical spaced notches disposed in transversely aligned pairs for receiving the rim of a can for positioning the top of a can in position for penetration by the punch, said notches permitting variation in the point of contact between the punch and the top of the can for varying the size of the opening formed therein.

2. A can opener comprising a frame having a pair of spaced parallel side members disposed in vertical relation and terminating in free vertical end edges, a punch pivotally mounted between said side members, an elongated handle extending integrally from said punch for moving the punch, said free end edges of said side members having vertical spaced notches disposed in transversely aligned pairs for receiving the rim of a can for positioning the top of a can in position for penetration by the punch, said notches permitting variation in the point of contact between the punch and the top of the can for varying the size of the opening formed therein, said notches having downwardly and inwardly inclined lower edges for forming pointed upwardly facing corners for hooking under the rim of a can for secure engagement therewith.

3. A can opener comprising a frame having a pair of spaced parallel side members disposed in vertical relation and terminating in free vertical end edges, a punch pivotally mounted between said side members, an elongated handle extending integrally from said punch for moving the punch, said free end edges of said side members having vertical spaced notches disposed in transversely aligned pairs for receiving the rim of a can for positioning the top of a can in position for penetration by the punch, said notches permitting variation in the point of contact between the punch and the top of the can for varying the size of the opening formed therein, said punch comprising a generally flat V-shaped member having sharpened edges and a downwardly tapering free end for engaging the top of a can radially inwardly of the rim thereof and cutting a V-shaped aperture therein and bending the material cut downwardly alongside the inner surface of the can, said notches permitting variation in the radial point of contact between the punch and can top thereby varying the size and radial extension of the apertures.
